UNITED STATES PATENT OFFICE.

WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA.

INSULATOR.

1,296,587.

Specification of Letters Patent.

Patented Mar. 4, 1919.

Application filed April 5, 1917. Serial No. 159,956.

To all whom it may concern:

Be it known that I, WILLIAM SCHAAKE, a citizen of the United States, and a resident of Pittsburgh, in the county of Allegheny and State of Pennsylvania, have invented a new and useful Improvement in Insulators, of which the following is a specification.

My invention relates to insulators for electrical conductors, and it has for its object 10 to provide a conductor-supporting means to be used with insulators of the above designated type.

Such insulators as have heretofore been proposed have employed some form of cable-securing clamp which retained the cable in a fixed position relative to the insulator. In such insulators, an excessive strain is imposed upon the insulating member and the cable is subjected to a sharp bend whenever 20 the insulator or clamp is slightly out of alignment with the supported conductor.

According to my invention, I provide an insulator of the above designated type with a cable-securing means which enables the 25 clamps to swing into alignment with the supported conductor and thereby prevent abnormal strains from being imposed upon the insulating member. Furthermore, a device constructed in accordance with my invention permits the same kind of insulator to be used at points where the conductor line 30 changes in direction and along the straight portions of the line.

Figure 1 of the accompanying drawing is 35 a top plan view of an insulator constructed in accordance with my invention; Fig. 2 is a view, partially in section and partially in elevation, taken on the line II-II of Fig. 1; and Fig. 3 is a sectional view taken on the 40 line III-III of Fig. 1.

The device shown in the drawing comprises an insulator 1 that is provided with a cap 2 which, in turn, supports an electrical conductor 3 by means of a plurality of clamps 4. The insulator 1 may be of any familiar type that is employed for structures of the above designated class. The cap member 2 is secured to the insulator 1 by cement 5, or other securing means, and 45 is provided with an annular rib 6 and a plurality of cable-positioning lugs 7. The rib 6 is interrupted to provide an opening 8 for a purpose to be hereinafter set forth and is of a cross-section, preferably of approximately circular form, that will suitably in-

terlock with a portion 9 of the clamp 4. The lugs 7 extend upwardly from the top of the cap 2 to provide a groove thereacross having a restricted central portion that is of just sufficient size to snugly admit the supported cable and have divergent ends which provide a materially wider groove at the rim of the cap 2. Each clamp 4 has a recess therein for gripping the supported conductor 3 and a recess in the portion 9 that is substantially at right angles to the first recess and is adapted to be slidably mounted upon, and interlocked with, the rib 6 to hold the cable 3 in place. The recessed portion 9 is adapted to fit the rib 6 with sufficient looseness to permit a considerable degree of movement of the clamps 4 in both a vertical and a horizontal plane without releasing the cable 3. Fig. 1 illustrates the approximate position that one of the clamps 4 assumes 75 when the cable is caused to make a sharp bend, and Fig. 2 shows the positions taken by the cable and clamps when there is a considerable degree of sag between supporting points. A bolt 10 is employed for securing 80 each clamp 4 to the conductor 3.

Such an insulator as I have herein described is assembled by sliding the recessed portion 9 of the clamp 4 over the rib 6 through the opening 8 and around to its operative position upon the rib. The cable 3 is then positioned in the groove across the insulator and gripped in the clamps 4 by tightening the bolts 10.

It will be understood that, if the portions 90 11 and 12 of the supported conductor are not in alignment during operation, the clamps 4 will slide along the rib 6 and adjust themselves to alignment with the corresponding portions of the supported conductor. The flared ends 13 of the upwardly projecting lugs 7 prevent the clamps from ever swinging around the rib 6 to such a degree that they will reach the opening 8 and become disengaged from the rib. Furthermore, the movability of the clamps upon the rib 6 prevents sharp kinks from being formed in the supported conductor at the points where the conductor leaves the insulator.

While I have shown and described a particular form of my invention, changes may be effected therein, without departing from the spirit and scope thereof, as set forth in the appended claims.

1 claim as my invention:

1. An insulator comprising a plurality of upwardly extending cable-positioning lugs, a rib, and clamps adapted to be slidably secured to said rib to hold the cable in place.
5. An insulator comprising a top having upwardly-extending cable-positioning lugs, a rib, and clamps adapted to be secured to said cable and to slidably engage the said
10. rib.
15. 3. An insulator comprising a rib, means for positioning a wire at the center of the insulator, and clamps adapted to engage said wire and be slidably held upon said rib.
20. 4. An insulator comprising a cap having a rib, clamps adapted to be slidably positioned on said rib and provided with wire-securings jaws, and means for positioning the wire at the center of the top of said insulator.
25. 5. The combination with an insulator having a wire-receiving groove and a rib, of a clamp slidably held on said rib and adapted to hold the wire in place on said insulator.
30. 6. The combination with an insulator constructed to receive a wire and having an outer rib, of a clamp adapted to be slidably received upon said rib and to be secured to said wire to hold the same in place.
35. 7. The combination with an insulator, of a cap for said insulator having a groove thereacross and a rib, said groove having a restricted central portion, said rib being interrupted at one side of the cap, a clamp

adapted to be applied to the rib through 35 the interruption space and to be rigidly secured to a cable.

8. The combination with an insulator, of a cap member provided with a rib extending nearly around the periphery thereof, and 40 clamps adapted to be slidably secured upon said rib, said rib and clamps serving to secure an electrical conductor to said cap and the interruption in said rib being for the purpose of permitting the rib to receive said 45 clamps.

9. An insulator comprising a cap having a ring shaped rib that is interrupted at one side, a plurality of upwardly-extending lugs on said cap for positioning a cable, and a 50 plurality of clamps adapted to be slidably received by said rib and to grip the cable, the interruption in said rib being for the purpose of permitting said rib to receive 55 said clamps.

10. An insulator comprising a plurality of cable-positioning lugs, an annular rib having an opening at one side, and clamps adapted to be slidably received by said rib through said opening and to grip said cable, 60 the engagement of said cable and said lugs being adapted to prevent the disengagement of said clamps and said rib after said clamps are positioned on said cable.

In testimony whereof, I have hereunto subscribed my name this 26th day of March 1917.

WILLIAM SCHAAKE.
